UNITED STATES PATENT OFFICE.

WILLIAM J. KEEP, OF DETROIT, MICHIGAN, ASSIGNOR TO THE MICHIGAN STOVE COMPANY, OF DETROIT, MICHIGAN, A CORPORATION OF MICHIGAN.

ELECTRIC FLAT-IRON.

1,155,423.

Specification of Letters Patent.

Patented Oct. 5, 1915.

Application filed January 29, 1915. Serial No. 4,977.

To all whom it may concern:

Be it known that I, WILLIAM J. KEEP, a citizen of the United States of America, residing at Detroit, in the county of Wayne 5 and State of Michigan, have invented certain new and useful Improvements in Electric Flat-Irons, of which the following is a specification, reference being had therein to the accompanying drawings.

10 This invention relates to electric flat irons of that type disclosed by the patents to Charles P. Madsen, No. 1098791, granted April 21, 1914, and No. 1099988, granted June 16, 1914.

15 Among the salient features of this invention may be mentioned three styles of terminal clamps and housings which permit of easy access being had to the terminals; a novel iron body or housing for a heating

20 unit which is constructed to be easily and correctly installed; a novel cord exit that prevents wear at the point of connection to the iron; a rear stand that co-operates with the cord exit in supporting the iron on end;

25 a handle practically free of heat radiation and, consequently cold; a switch conveniently located for controlling electric circuits of the iron, and a guard plate that permits of easy access being had to electric conductors and other parts of the iron.

30 A flat iron characterized by the above devices possesses many advantages, which will more readily appear as the nature of the invention is better understood, the same residing 35 in the novel construction, combination and arrangement of parts hereinafter described and claimed.

The essential features of the invention, involved in carrying out the above, are necessarily 40 susceptible to a wide range of structural modification without departing from the spirit or sacrificing any of the advantages of the invention, but a practical embodiment thereof is suggested in the drawings, wherein—

Figure 1 is a longitudinal sectional view 45 of an electric flat iron in accordance with this invention; Fig. 2 is a plan of the upper housing or section of the iron body; Fig. 3 is a bottom plan of the upper housing or section; Fig. 4 is a perspective view of a 50 detached spider and handle bail carried thereby; Fig. 5 is a perspective view of the detached terminal housing; Fig. 6 is a cross sectional view taken on the line VI—VI of

Fig. 1; Fig. 7 is an elevation, partly in section, of a modified form of terminal housing; Fig. 8 is a horizontal sectional view taken on the line VIII—VIII of Fig. 7; Fig. 9 is an elevation of a further modified form of terminal housing; Fig. 10 is an end view of the same; Fig. 11 is a side elevation of the flat iron, on a small scale, illustrating the iron on end; Fig. 12 is a similar view of a simplified iron; Fig. 13 is a longitudinal sectional view illustrating a modified iron body or terminal housing provided with a heating unit; Fig. 14 is a plan of the same; Fig. 15 is a cross sectional view taken on the line XV—XV of Fig. 13; and Fig. 16 is a cross sectional view taken on the line XVI—XVI of Fig. 2.

In the drawings, 1 denotes a lower housing having a polished surface 2 and a chambered or cut away peripheral edge providing a seat 3 for the walls 4 of an upper housing 5, the housings 1 and 5 constituting the body of the flat iron. With the walls 4 upon the seat 3 the housings are spaced and provide clearance for a heating unit which is insulated relative to the body of the iron. The insulation consists of two sheets of mica 6 and 7 and for the convenience of handling the mica sheet 6, the sheet is riveted or otherwise connected to a thin metallic plate 8 and this metallic plate is placed upon the housing 1 with the mica sheet uppermost. The mica sheet 7 is connected to a metallic plate 9 by eyelets 10 and these eyelets are also employed for retaining heating elements against the sheet of mica 7. The heating elements are in the form of flat strips of insulation 11 separately wound with a resistance ribbon 12, said ribbon connecting the elements at the reduced ends 13 of the plates. These ends of the plates are reduced in order that the same can extend throughout the length of the heating unit, and as shown in Fig. 3, the elements have a V-shaped formation or diverge from the forward end of the heating unit. By connecting the heating element to the sheet of mica 7 of the metallic plate 9 the heating unit possesses solidity and facilitates handling.

As constructed, the heating unit is a bench assembled proposition and this is also true in connection with the metallic plate 8 and the sheet of mica 6, although in some instances these two may not be connected together, but with the heating elements the

use of the eyelets 10 or similar fastening means is essential in order that the heating elements will not become accidentally displaced.

- 5 The housing 5 is provided with an oblong recess 14 and the bottom of said recess has openings 15 alining with openings 16 in the heating unit and sockets 17 in the housing 1, said sockets having the walls thereof screw-threaded to receive screws 18 employed for holding the housing 5 upon the housing 1. The screws 18 have large elongated hexagonal heads 19 and the openings 16 of the heating unit are of sufficient size to provide 10 clearance for the screws 18.

Oppositely disposed walls of the recess 14 are provided with bosses 20 and bearings or seats 21, the latter accommodating the legs 22 of a spider 23 retained in a horizontal 15 position by screws 24 entering the bosses 20. The spider 23 has large openings 25 providing clearance for the heads 19 of the screws 18 and besides these openings there is a central opening 26, the purpose of which will 20 hereinafter appear. With simply the legs 22 of the spider supporting the same there is an air gap between the spider and the walls of the recess 14 and this air gap is essential in order to maintain the spider 25 and parts carried thereby as cool as possible during the use of the iron.

Riveted or otherwise connected to the ends of the spider 23 are handle supports 27 and 30 and the handle support 27 terminates in an apertured bearing 29. Adjacent to the bearing 29 is a switch socket 30 provided with a switch housing 31 somewhat after the type of switch disclosed by the Madsen Patent No. 1,099,988. The switch housing 35 has push buttons for controlling the electric circuit of the iron and suitable designations, as "off" and "on."

The support 28 terminates in an apertured bearing 32 which coöperate with the bearing 29 in supporting a handle 33. The handle 33 is retained upon the bearings 29 and 32 by an axial tie rod 34 extending through the bearings 29 and 32. The supports 28 serve functionally as a stationary member or back 40 of a terminal housing 35. The housing 35 is held in engagement with the support 28 by screws 36 entering bosses 37 forming part of the support 28, and the upper end of the housing 35 coöperates with the upper end 45 of the support 28 in providing a flared mouth piece or a bell shaped exit 37 that receives a coiled wire protector 38 of an insulated conductor cord 39. This cord is 50 of the ordinary and well known type employed for supplying electricity to the iron and the end of the cord is bared and the ends of the electric conductors separated by a prong 40 projecting from the support 28.

Contiguous to the lower end of the supports 28 are sets of lugs 41 serving as

spacers for insulated conductors 42 and 43, which have the ends thereof bared against a sheet of insulation 44, as mica, arranged against the support 28, between the sets of lugs 41 and the bosses 37. This sheet of mica is cut away to provide clearance for the prong 40 and said sheet is held against the support 28 by the head of a small screw 45 mounted in the support 28.

The bared ends 46 of the cord conductors 70 are held in frictional contact with the bared ends of the conductors 42 and 43 by a novel clamp in the housing 35. The side walls of the housing 35 are recessed to provide ledges 75 47 and extending into the recesses of the 80 housing are the ends of a transverse metallic bar 48 which is placed in position by first placing one end of a bar in a recess and then the opposite end. Engaging the outer side of the metallic bar 48 is a strip of insulation 49, as mica, and this strip is placed in position by first placing one end thereof behind the ledge 47 and then bending the strip in order that the opposite end can be placed behind the other ledge. When released the strip assumes a position against the metallic bar 48 and is in position to engage the bared ends 46 of the cord conductors.

Engaging the inner sides of the metallic 90 bar 48 is a screw 50 and it is through the medium of this screw that pressure is brought to bear against the bar 48 independent of the screws 36 which attach the housing to the support 28. By adjusting the screw 50, the bared ends 46 of the cord conductors are firmly clamped against the bared ends of the conductors 42 and 43, and in consequence of the terminal pressure there is a 95 perfect contact between the conductors. Since the clamp forms part of the housing 100 35, it is an extremely easy matter to remove the screws 36 and the housing 35 when it is desired to remove the cord 39, but since the cord and its coiled wire protector can 105 freely shift in the flared mouth piece or bell shaped exit 37, it is hardly ever necessary to remove the cord. The bell shaped exit prevents sharp bending of the cord and consequently the longevity of the same is materially increased.

The conductor 42 extends lengthwise of the spider 23 and is connected to the switch socket 30, as at 51 and another conductor 52 is connected to the switch socket, as at 53. 110 This last mentioned conductor extends through the central opening 26 of the spider 23 in proximity to the end of the conductor 43, and the ends of both conductors are bared, as at 53. These ends of the conductors extend through large openings 64 in the bottom of the recess 14, large openings 54 of the metallic plate 9 and small eyelet openings 55 of the sheet of mica 7. The small eyelet openings 54 center the ends of the con- 115 120 125

ductors relative to the large openings 54, thereby precluding any possibility of the conductors contacting with the metallic plate 9. The bared ends 53 of the conductors 5 are laterally and oppositely disposed to positively contact with the ends of the heating elements composing the heating unit, as best shown in Fig. 3.

The principle of applying pressure to the bared ends of the conductors, as disclosed in connection with the housing 35, is also applied to the bared ends 53 of the conductors 43 and 52. This is accomplished by placing pressure screws 56 in the housing 15 5, at the rear end of the recess 14 and directly above the rear ends of the heating elements, whereby when said screws are adjusted pressure is brought to bear upon the metallic plates 9 to clamp the rear ends of 20 the heating elements upon the bared ends 53 of the conductors.

Mounted over the spider 23 is a sheet metal guard plate 57 that is spaced from the housing 5 and consequently provides an 25 exit for heat. One end of the guard plate 57 extends under a transverse lip 58 of the support 28 and the opposite end thereof terminates in a gooseneck 59 held between the bearing 29 and the end of the handle 30 33. The guard plate 57 is in the form of a hood or canopy that prevents radiation of heat toward the handle 33 of the iron and such hot air as escaped by the air gap at the marginal edges of the recess 14 is 35 deflected downwardly and away from those elements supporting the handle 33. The guard plate 57 covers the conductors 42 and 52 and finishes off the exterior appearance of the iron.

Connected to the rear end of the housing 5 by screws 60 or other fastening means are the end flanges of a projection 61 and this projection is adapted to coöperate with the flared mouth piece or bell shaped exit of the 45 housing 35 in supporting the iron on end, whereby the polished surface 2 of the iron is maintained out of engagement with a table or ironing board, thereby obviating the necessity of using an iron rest or temporarily 50 turning off the current.

Before further considering the iron just described, it is thought best to refer to a few modifications, and reference will first be had to Figs. 12 and 15 inclusive. The 55 iron body shown in these views is composed of two housings 62 and 63 connected by screw bolts 64 and the housing 62 is adapted to be inclosed by a suitable cover 63^a. The recess 14, spider 23, switch 31 and projection 61 are dispensed with, thus simplifying the iron, and conductors can be arranged over the iron body for a heating unit 65, similar to the unit previously described.

This heating unit can be clamped between 60 the housings 62 and 63, and the views illus-

trating this modification clearly show pressure screws 66^a for the heating element and the manner in which the bared ends of conductors are held in engagement with the elements.

70

A further modified form of terminal housing is illustrated in Figs. 7 and 8, wherein 75 66 denotes a housing having a wall 67. The housing 66 is in the form of a yoke suitably connected to the wall and said wall is provided with openings 68. Countersunk in the wall 67 at the ends of the openings 68 are washers of insulation 69, preferably made of mica, and concentrically of said washers and out of engagement with the wall 67 are 80 screws 70 retained in engagement with the washers by nuts 71. The threaded ends of the screws 70 extend into metallic sleeves 72 and interposed between the ends of said sleeves and the nuts 71 are the eye ends 73 85 of terminals or conductors 74. The opposite ends of the sleeves 72 are engaged by a sheet of insulation 75, as mica, held against the ends of the sleeves by a bar or plate 76 engaged by a tension or pressure screw 77 90 95 adjustable in the housing 66. The walls of the sleeves 72 are of sufficient thickness to bear strongly against the eyes of the terminal and there is no possible chance of the terminals becoming accidentally misplaced. 95 The screw 77 permits of sufficient pressure being brought to bear to firmly hold the terminals and insure a positive contact and it is possible to adjust the screws 77 from time to time to insure a perfect electrical 100 connection.

A very simple form of terminal housing, has been shown in Figs. 9 and 10. The housing in this instance, comprises members 78 and 79 connected by a screw bolt 80 105 and a nut 81. The members 78 and 79 have abutting ends 82 and the opposite ends of said members are faced with pieces of insulation 83, as mica, between which are clamped the bared ends 84 of conductors. 110 By adjusting the nut 81 sufficient pressure can be brought to bear upon the bared ends of the conductors or terminals to crush the same and provides a positive connection between the terminals.

115

The terminal clamps disclosed by all the 115 housings can be used for terminals of other heating devices than electric flat irons.

From the foregoing it will be observed that the body of the iron is composed of a 120 housing and considering the heating elements as electric conductors, that the housing contains the ends of electric conductors that are held in positive contact either by the means connecting the sections of the 125 housing together, or by such means as the pressure screws 56. In all instances two members are employed to form a housing and the manner in which the members are assembled permits of easy access being had 130

to the terminals held between the members. This is particularly true in connection with the iron body, as by removing the guard plate 57 and the screws 18, the housing 5 can be bodily removed from the housing 1 and the heating unit repaired or renewed should occasion require. Considerable importance is attached to the flared mouth-piece for bell shaped exit of the support 28 and housing 35, as with the iron on end the upper end of the support 28 provides sufficient clearance for the cord 39 without any danger of the cord being sharply bent or injured. Furthermore, the novel manner 10 in which the overlapped terminals are sandwiched between plates of insulation backed by substantial bodies is also a feature of the invention, as it is practically impossible for short circuits to occur or conductors become 15 disarranged during the use of the iron.

What I claim is:—

1. An electric flat iron comprising housings, a heating unit clamped between said housings, a spider in one of said housings 25 providing an air gap, handle supports carried by said spider, a housing connected to one of said handle supports, a conductor cord extending into said housing in circuit with said heating unit and a switch carried 30 by the other support and in circuit with said heating unit and said conductor cord for controlling the operation of said iron.

2. An electric heating device, comprising a flat insulation plate, a winding thereon, insulated lead in wires having bared ends superimposed upon the ends of said winding, a flat plate of insulation superimposed upon said winding, a flat metallic plate superimposed upon said insulating plate, housings 35 above and below the assembled plates adapted to clamp said plates together except at a spot over the contact points at the ends of said winding and the bared ends of said lead in wires, and a pressure screw adjustable in 40 the upper housing and operable from without the device to force together the bared ends of said wires and the ends of said winding between the core of the winding and the superimposed plate of insulation.

3. An electrical flat iron comprising housings, a laminated heating unit compressed between said housings, insulated terminals passing through holes in the upper housing, one bared end of one of said terminals lying 55 upon the end windings of said unit between laminations thereof, and means, other than the connecting means which unite said housings, for clamping together the bared ends of the insulated terminals, and the end windings of said unit.

4. In an electric flat iron, a heating unit, a flat plate of insulation on each side thereof, an insulated terminal having bared ends placed between the plates of insulation and 60 bared resistance of the heating unit, means

operable from outside the iron for clamping the bared surfaces together beneath the upper plate of insulation, and a metal plate under the clamping means and over the upper sheet of insulation to prevent injury to 70 the insulation plate.

5. In an electric flat iron having a heating unit made by winding resistance wires on a flat insulating core, insulated lead in wires with bared ends superimposed on the last 75 coils of the winding, a sheet of resistance superimposed on both of these and having a hole properly formed in the upper sheet through which the lead in wires pass and fit closely to prevent displacement of the contacts.

6. An electric flat iron of which the top cover and the working bottom are housings between which a heating unit is clamped, the top housing having a recess in its upper surface, a detachable spider over said recess, said spider having ends rising as a bail, a handle carried by the bail of said spider, a switch at an end of said bail, and terminal wires rising from the heating unit at the 80 rear of the housing and passing through and over said recess to said switch.

7. In an electric flat iron, a working bottom, a top cover, a heating element compressed between said working bottom and top cover, said top cover having a recess in the top thereof, a spider spanning the recess of said top cover, handle supports rising from the ends of said spider, and a stationary housing on the rear handle support 95 adapted to connect said heating element to a heater cord, said housing having a flared exit adapted to prevent breakage of the heater cord by bending.

8. In a terminal connection for electric 105 heating devices, a sectional housing, sheets of insulation therein, conductors extending into said housing and having the ends thereof bared between said sheets of insulation, means for connecting the sections of said 110 housing together, and means independent of the last mentioned means for bringing pressure to bear upon one of said sheets of insulation to clamp the bared ends of said conductors together.

9. In a terminal connection for electric flat irons, a housing having open ends and one of the ends thereof flared, conductors extending into said housing and having the ends thereof bared, sheets of insulation in 120 said housing between which the bared ends of said conductors extend, means in said housing for positioning the bared ends of said conductors whereby the ends of conductors overlap, and means carried by said 125 housing to bring pressure to bear upon one of said sheets of insulation whereby the bared ends of said conductors are clamped together.

10. A terminal connection for an electric 130

- flat iron having a heating unit, comprising a rear handle support composed of half housings clamped together and having top and bottom openings, the top opening admitting a heater cord to said housing and the bottom opening admitting insulated terminals of the heating unit of an iron, the cord and insulated terminals having bared ends in said housing, sheets of insulation between the housing and the bared ends of the cord and terminal, and means in said housing adapted for clamping the bared ends of the cord to the bared ends of the terminal. 5
11. In an electric flat iron, a cover having in its upper surface a recess open at the top and no other openings for air circulation, a spider carrying at its ends handle supports and secured at its sides to the recess walls, and a guard plate suspended from the handle supports of said spider and free of said cover. 10
12. In an electric iron, a cover for said iron, handle supports indirectly carried by the cover of the iron, the rear support being composed of housings adapted for the bared ends of lead in connections, a guard plate carried by the handle support independent of said cover. 15
13. In an electric iron, a cover for said
- iron, handle supports indirectly carried by the cover of the iron, the rear support being composed of housings adapted for the bared ends of lead in connections, a guard plate carried by the handle support independent of said cover, and a switch on the front handle support. 20
14. In an electric iron, a cover, a bottom plate, a heating element clamped between said cover and said plate, a handle supported by said cover, a switch on the front handle support, and a guard plate supported by the handle supports and forming with said cover a conduit for wires to and from said switch. 25
15. In an electric flat iron, a clamping device for lead in wires, said device having a recess therein, a clamping plate shorter than the recess and slideable therein, and a sheet of insulation sprung into the recess of said device adapted to hold said clamping plate 30 therein. 35

In testimony whereof I affix my signature in presence of two witnesses.

WILLIAM J. KEEP.
